UNITED STATES PATENT OFFICE.

WILLIAM MACDONALD AND HUGH MACDONALD, OF INVERNESS, SCOTLAND.

WAVING OF HAIR.

Application filed November 3, 1925, Serial No. 66,371, and in Great Britain November 3, 1924.

This invention relates to apparatus for use in the waving of hair and of the type wherein steam is adapted to be injected or brought in contact with the hair wound upon a suitable curling device and mounted with a jacket whereby the hair is heated with moist humid heat.

An object of the invention is to provide improved means for closing the end of the jacket adjacent the roots of the hair when the device is in position so as to provide a tight joint to prevent escape of the steam.

The invention consists in a hair-waving appliance comprising in combination a jacket adapted for moist heat treatment of the hair, and means operatively connected to the scalp end of the jacket for facilitating the formation of a vapour-tight joint between the tress of hair and the jacket.

Said means may comprise a flexible sleeve element adapted to be inserted upon the jacket and having an outer beaded or thickened edge whereby the sleeve may be rolled to provide a ring to facilitate the tying of the sleeve to form the vapour-tight joint.

The accompanying drawings illustrate an improved jacket and jointing means according to the invention:—

Figure 1 being a sectional elevation of the jacket, with the improved joint-making device applied thereto.

Figures 2 and 3 being partial elevations of the left-hand end thereof and of a modified form, while

Figure 4 is a sectional elevation of the improved jointing means.

In carrying the invention into effect according to one convenient mode, a cylindrical tube 5 is provided with an opening at both ends and is adapted to accommodate a curler 6 of any suitable form upon which a tress of hair is wound.

Arranged on the outer face of the jacket is a small tube or pipe 7 adapted to convey steam to the interior of the jacket at the left-hand end thereof. The pipe 7 may be mounted upon the jacket in any convenient manner and may be positioned by distance pieces 8 on the jacket. The free end of the steam pipe may be clipped by the band, 9 and may project beyond the jacket whereby the necessary connection with the source of steam may be made.

For the purpose of enabling the curler to be positioned well within the jacket, the lat-

ter at the left-hand end is cut away as shown at 10, Figure 2, to accommodate the hair. By such means the steam entering by the port 11 will be caused first to impinge upon the roots of the hair afterwards travelling along the jacket to the outlet. Any suitable means may be provided by closing or partially closing the right-hand end of the jacket to control the flow of steam through the jacket.

As an alternative to the simple slot 10 as shown in Figure 2 the end of the jacket may be provided with a bayonet slot 12 as shown in Figure 3.

Instead of one orifice for the entry of steam, a number of orifices may be provided, all disposed at the "scalp" or left-hand end of the jacket. Thus at this point the jacket may have a double wall within the space between which the steam tube communicates, the inner wall being pierced at a number of places.

The steam jacket may be provided with heat insulating material on its outer surface whereby it may be more readily handled.

Instead of a single-walled jacket, a double-walled jacket may be provided. The jacket may also be adapted to open longitudinally for the reception of the curler or a pair of tubes sliding one upon the other may be arranged.

In order to close the scalp end of the steam jacket a short rubber sleeve 13, see Figures 1 and 4, is provided which has a part 14 of reduced diameter and which is adapted to be mounted upon the scalp end of the jacket. The other end of the rubber sleeve is beaded to provide a more or less stiff ring 15. Instead of the bead a ring made of metal or other suitable material may be attached to the sleeve. It is found convenient in practice, however, to employ a ring which is resilient so that the sleeve may be rolled back on to the jacket, the curler inserted into the jacket and the sleeve then unrolled on to the roots of the hair. A joint may then be made by encircling the sleeve just underneath the curler with a string or tape and tying at the point.

In sleeves hitherto employed for use in permanent waving it has always been difficult to provide a good joint as there were no means of ensuring that the edge of the sleeve would always lie or be caught by the string or clip used.

By means of the improved arrangement of

a more or less stiff ring 15 it is practically impossible to avoid making a proper joint as the ring will hold the sleeve in the correct position while tying is being effected.

5 According to a modified form the outer end of the flexible sleeve may be moulded so as to receive a displaceable metal or other ring.

In cases where the steam jacket is formed 10 of more or less flexible material, such as those formed of paper in which one end is flexible, the rubber sleeve may be dispensed with and the ring element may be formed directly upon such flexible end of the jacket.

15 Having now described our invention, what we claim as new and desire to secure by Letters Patent is:—

1. A hair-waving appliance comprising the combination of a jacket adapted for 20 moist heat treatment of the hair, and a flexible sleeve element adapted to be mounted upon the jacket at the scalp end thereof, said sleeve having an outer beaded edge adapted to facilitate the formation of a vapour-tight joint between the tress of hair and the 25 jacket at the scalp end thereof.

2. A hair-waving appliance comprising a tubular jacket adapted for moist heat treatment of the hair and having one end of a 30 flexible nature and adapted to be tied upon the hair to form a vapour-tight joint, and a ring element carried by said end whereby the formation of said joint is facilitated.

3. A hair-waving appliance comprising in combination a tubular jacket adapted to enclose a hair-waving device having the hair wound thereon, a conduit mounted longitudinally of the jacket and connected to the interior of the jacket so as to cause steam to impinge upon the root ends of the hair and a rubber sleeve mounted on the jacket, and a beaded edge formed on the outer end of the sleeve.

4. A hair-waving appliance as claimed in 45 claim 3, wherein the tube is slotted longitudinally at the scalp end for the purposes set forth.

5. Joint forming means for use with hair-waving appliances having a tubular jacket, comprising a cylindrical rubber sleeve of stepped diameter form, the outer edge of the part of larger diameter being beaded to provide a substantially stiff edge, the part of smaller diameter being adapted to be mounted upon and grip the scalp end of the 55 jacket.

6. A hair-waving appliance as claimed in 60 claim 3, wherein the jacket is provided with a circumferential series of apertures to which steam is led by the longitudinally arranged conduit.

In testimony whereof we have signed our names to this specification.

WILLIAM MACDONALD.
HUGH MACDONALD.
